(57) **CLAIM**

The ornamental design for a combined transmitter and receiver for home network, as shown and described.

DESCRIPTION

1. Combined transmitter and receiver for home network

1.1 : Perspective

1.2 : Front

1.3 : Left

1.4 : Top

1.5 : Bottom

1.6 : Perspective, in position of use

The broken lines depict portions of the combined transmitter and receiver for home network that form no part of the claimed design.

Reproduction 1.1 is a front perspective view of the combined transmitter and receiver for home network; reproduction 1.2 is a front view thereof where the back view is a mirror image; reproduction 1.3 is a left view thereof where the right view is a mirror image; reproduction 1.4 is a top view thereof; reproduction 1.5 is a bottom view thereof, the bottom surface being flat; and reproduction 1.6 is a perspective view thereof showing an example of the usage of the subject design in operation. The design consists of a globular sensor and a cylindrical body. When the transmitter gives notification, the globular sensor floats in the air, as seen in reproduction 1.6.

1 Claim, 6 Drawing Sheets
